UNITED STATES PATENT OFFICE.

JOHN L. RUSSELL, OF TROY, NEW YORK.

COMBINED PAPER-WEIGHT AND CIGAR AND ASH HOLDER.

SPECIFICATION forming part of Letters Patent No. 371,901, dated October 18, 1887.

Application filed March 21, 1887. Serial No. 231,636. (No model.)

To all whom it may concern:

Be it known that I, JOHN L. RUSSELL, of the city of Troy, county of Rensselaer, State of New York, have invented a new and useful 5 Combined Paper-Weight and Cigar and Ash Holder, of which the following is a specification.

My invention relates to a device that by its construction is arranged to perform the functions of a paper-weight, cigar-holder, and ash-holder, all of which functions it is adapted to perform at the same time and in connection, as distinguished from a combination device or tool in which the several parts perform several functions disconnectedly.

It is the object of my invention to combine with a paper-weight that is adapted for its ordinary use upon a table or desk an added construction consisting of a groove made longitudinally in the top of the paper-weight, said groove being adapted to receive a lighted cigar when temporarily laid thereon by the smoker, and a sink, also made in the top of the paper-weight at one end of said groove, so that 25 the cigar within the groove may have its lighted end extending over the sink, where the air can circulate around it.

Where a lighted cigar is temporarily laid down with its edge projecting beyond the edge 30 of the table whereon placed, it is liable to roll off, and when laid down on a table or surface without having its edge overhang it is liable to burn that on which it rests as well as to go out, and the wet end of the cigar stains the 35 surface of whatever it rests upon. All of these difficulties my invention is intended to obviate.

Accompanying this specification, to form a part of it, there is a sheet of drawings containing four figures illustrating my invention, with 40 the same designation of parts by letter-reference used in all of them.

Of the illustrations, Figure 1 shows a perspective of a device containing my invention applied as a combined paper-weight and cigar and ash holder. Fig. 2 shows a longitudinal 45 central section taken on the line x' x' of Fig. 1. Fig. 3 shows a cross-section taken on the line x^2 x^2 of Fig. 1. Fig. 4 shows a cross-section taken on the line x^3 x^3 of Fig. 1.

The several parts of the device thus illustrated are designated by letter-reference, and the function of the parts is described as follows:

The letter B designates the body of the device made of such metal or other material as will give sufficient weight to it to keep papers 55 in place when resting with its bottom surface thereon.

The letter G designates a groove made in the top of the body longitudinally, and S a sink made therein at one end of said groove. 60

The letter O indicates a cigar placed therein.

As thus made and arranged the device performs all the functions for which it is designed connectedly and conveniently.

Having thus described my invention, what I 65 claim, and desire to secure by Letters Patent, is—

A combined paper-weight and cigar and ash holder constructed with a body part that is adapted to rest upon papers to keep them in 70 place, and made with a longitudinal groove suited to receive a cigar, and a sink formed within the body part at one end of said groove, substantially in the manner, as and for the purposes set forth.

Signed at Troy, New York, this 8th day of February, 1887, in the presence of the two witnesses whose names are hereto written.

JOHN L. RUSSELL.
